HIGH CHAIR

Paul S. Kinstley, Portland, Tex., assignor to Oro-Lanza Enterprises, Inc.

Filed Sept. 3, 1970, Ser. No. 24,826

Term of patent 14 years

Int. Cl. D6—02

U.S. Cl. D15—1

FIG. 1 is a perspective view of a high chair embodying the novel design showing the front and right side thereof.

FIG. 2 is a view of the left side of the chair.

The rear of the chair is without ornamentation significant to the design.

I claim:

The ornamental design for a high chair, as shown and described.
